VEHICLE TOY

John W. K. Heppner, New York, N. Y., assignor
to Louis Marx & Company, New York, N. Y., a
corporation of New York

Application June 10, 1933, Serial No. 675,221

5 Claims. (Cl. 46—48)

This invention relates to vehicle toys and more particularly to such toys equipped with a sound producing siren.

The object of the present invention is to generally improve vehicle toys, especially such toys simulating vehicles which ordinarily carry and use a siren. The toy may, for example, simulate a fire engine or fire department vehicle, a police car, an ambulance, an emergency truck, or the like. A more particular object of the present invention resides in the provision of a vehicle toy carrying a miniature or toy siren appropriately actuated by a driving motor or from the wheels of the vehicle to produce a wailing or shrieking sound imitative of the sirens employed as aforesaid.

If the siren is simply directly geared to the vehicle wheels or to a motor or both, the operation of the siren is arrested if the motor or vehicle is stopped. In accordance with a further feature and object of the present invention, the gearing driving the siren includes a freely disengagable element affording overrunning rotation of the siren, that is, the drive is made such that the siren is accelerated when the vehicle accelerates, and in fact, tends to limit or govern the vehicle speed, but the siren is free to rotate at its own natural speed if the vehicle abruptly decelerates. In fact, due to the very high step-up ratio employed in the gear train the result is in the nature of a kick-off mechanism which sets the siren into effective operation upon even slight movement of the driving motor. This greatly enhances the realism of the toy, for one striking characteristic of the siren is the natural change in pitch and dying out of sound which occurs when the siren is permitted to slow up at its natural speed instead of being abruptly stopped when the vehicle is stopped or substantially slowed down.

To the accomplishment of the foregoing and such other objects as will hereinafter appear, my invention consists in the vehicle toy and siren elements and their relation one to the other as hereinafter are more particularly described in the specification and sought to be defined in the claims. The specification is accompanied by a drawing in which:

Fig. 1 is a side elevation of a toy embodying my invention;

Fig. 2 is an inverted plan view thereof; and
Fig. 3 is a section taken in the plane of the line 3—3 in Fig. 2.

Referring to the drawing, the vehicle toy comprises a vehicle body 12 having mounted thereon front wheels 14 and rear wheels 16, the front

wheels being freely rotatable and the rear wheels preferably being driven by an appropriate motor exemplified in the present case by a spring energized motor 18. The vehicle toy is further equipped with a miniature or toy siren 20 which is geared by appropriate step-up gearing 22 to the motor 18 and thence to the wheels 16. Considered in one aspect, the siren 20 is geared to the wheels 16 and is thereby adapted to be rotated upon movement of the vehicle. In such case the vehicle need not have a motor but may be pulled. In another aspect the siren 20 is geared to a driving motor 18 which is used for propelling the vehicle and operating the siren.

Considering the arrangement in greater detail, the vehicle body 12 is made of sheet metal parts pressed to desired configuration and secured together by tongue and slot connections. The body may simulate a fire engine or, as in the present case, a roadster such as is used by the fire chief. The body might equally well simulate a closed coupé or other body type, but in any case when simulating a fire department vehicle it is, of course, preferably colored red.

The wheels 14 and 16 may be made of rubber, simulating the tires used on automobiles. The front wheels 14 are mounted for free rotation on a spindle 24 which is carried in the front axle and bumper support 26 which in turn is pivoted at 28 to permit steering of the toy.

The rear wheels 16 are mounted on an axle 30 carried in a motor frame 32 the side walls 34 and 36 of which house and journal the motor mechanism. This may, of course, be of conventional type and comprises a winding stem 38 bent to form a winding key 42 and having connected thereto the inner end of a spring strip 44, the outer end of the spiral spring being connected to the motor frame as is indicated at 46. The stem 40 further carries the driving portion of an appropriate ratchet 48 which cooperates with a main driving gear 50 which is otherwise freely rotatable on stem 40. Gear 50 meshes with pinion 52 which in turn rotates gear 54 meshing with pinion 56 which in turn is mounted 45 on the rear wheel axle or drive shaft 30 and thus terminates the gear train of the wheel driving mechanism. It will be understood that when winding the spring, ratchet 48 permits the wheels to be held or locked against rotation, and that upon release of the winding key the unwinding of spring 44 rotates the winding stem and the driving portion of ratchet mechanism 48, which in turn rotates gear 50 and consequently the gear train of the vehicle.

The winding stem 40 is preferably elongated to extend beyond the side wall 34 of the motor frame to the opposite side of the vehicle. The remote end of the winding stem passes through 5 and forms a part of the siren gear train 22. The latter is housed within appropriate side walls 60 and 62 which journal the various spindles of the gear train. The gear train consists of a main drive gear 64 mounted directly upon the winding stem 40 and meshing with a pinion 66 which in turn rotates a gear 68 meshing with a pinion 70 mounted on freely rotatable spindle 72 which also carries a gear 74 meshing with a pinion 76 mounted upon the siren shaft 78.

15 It should be noted that while this gear train may, if desired, be a simple gear train providing positive interconnection between the winding stem 40 and the siren shaft 78, it preferably is modified to include a freely disengageable element affording overrunning rotation of the stem. For this purpose the spindle 72 is carried in slots 80 in the side walls 60 and 62, these slots being so directed as to maintain the gear 68 and the pinion 70 in meshing relationship but 25 permitting the gear 74 to move away from and disengage the siren pinion 76. It will further be noted by reference to the arrows in Fig. 3, that the direction of rotation of the gears is such that when the spring motor unwinds, the 30 gear 68, rotating counterclockwise as viewed in Fig. 3, tends to move gear 74 into engagement with pinion 76. On the other hand, when no driving impulse is being imparted by the motor, the gear 74 tends naturally to fall away from 35 pinion 76 both due to gravitational influence and more importantly because the rotation of gear 74 and pinion 76 is in such direction that these parts run downwardly about the periphery of gear 68 whenever gear 68 is stopped or slowed 40 down. As a result of this construction the siren is permitted to overrun, as though driven by a one-way clutch, but, because of the complete disengagement of the parts, it overruns in a substantially frictionless manner which permits 45 sustained and gradual deceleration of the siren.

The siren itself comprises a housing made up of a shallow cup-shaped part 80 closed by a cap 82, the housing being apertured with appropriate 50 openings 84 and 86. Within the housing there is rotatably supported an impeller 88 which may be of conventional type and is mounted on one end of spindle 78.

The provision of separate housings for gear trains 18 and 22 is of advantage to the manufacturer because he can make some toys without the siren equipment. In other words, the 55 separate siren equipment may be added to a part of the line.

In the present embodiment of the invention 60 the fire patrol vehicle has seated therein a toy fireman including a body portion 90 having arms 92 holding a simulated steering wheel 94 and having a head 96 with helmet 98 mounted for movement relative to the body 90. Specifically, 65 in the present case the head is mounted at the upper end of a vertical shaft the lower end of which carries a face gear or pressed radially corrugated member 100 (see Fig. 2) which rests upon and meshes with a gear 102 mounted at the center portion of winding stem 40. This arrangement causes the helmeted head to rotate 70 completely around the body as the vehicle travels, thereby producing a ludicrous effect which may be heightened by giving the face 96 75 a comical appearance. The toy may be provided

with a bell 104 in further simulation of this class of vehicle.

In operation, the toy is wound by means of the winding key 42. The kick-off effect produced by the very high step-up ratio of the siren gear train 22 with the disengageable gear 74 is so sensitive that the siren is spun and audibly operated by even that slight restoring movement of the key which takes place as the ratchet teeth 48 come into holding relation. The child is thus able 10 to operate the siren preliminarily while winding the toy, with a series of short siren impulses indicative, for example, of the fact that the vehicle is about to start. If preferred, the toy may be wound silently by operating the winding key relatively slowly and carefully so as not to provide noticeable propulsion or kicking-off of the siren. When the toy has been wound and is released, it moves forward with accompanying sounding of the siren. The siren load has a speed limiting 20 effect on the vehicle when the vehicle is not obstructed. In ordinary use the progress of the toy is, however, often arrested, as by meeting an obstacle in the room, whereupon the toy is abruptly stopped but the siren continues its 25 sounding in a natural and realistic manner, indicative of the fireman's desire to have the path cleared. In practice the child may often decelerate or stop the toy in order to purposely produce a change in tonal value of the siren, and this 30 desirable and realistic effect is, in fact, caused by the vehicle meeting and rolling over bumps or similar minor obstructions.

It is believed that the mode of constructing and using, and the many advantages of my invention, will be apparent from the foregoing detailed description thereof. It will further be apparent that while I have shown and described my invention in preferred form, many changes and modifications may be made in the structure 40 disclosed, without departing from the spirit of the invention, defined in the following claims.

I claim:

1. A toy vehicle comprising a toy body, wheels mounted thereon, a siren, and a step-up gear 45 train interconnecting a wheel and said siren in order to impart rapid rotation to the siren upon movement of the vehicle, said gear train including a freely automatically disengageable element affording free overrunning rotation of the siren 50 whenever the vehicle decelerates faster than the natural rate of deceleration of the siren.

2. A toy vehicle comprising a vehicle body, a spring energized driving motor, wheels, a siren, and gearing interconnecting the wheels, motor, 55 and siren to impart high speed rotation to the siren upon movement of the vehicle, the part of said gearing leading solely to said siren including an automatically disengageable element to permit free overrunning of the siren upon stop- 60 page of the vehicle.

3. A toy vehicle comprising a body, wheels mounted thereon, a siren mounted thereon, a spring drive motor having a main winding stem, a gear housing and a train of step-up gearing 65 therein interconnecting the stem and a wheel, and a second and independent gear housing and a train of step-up gearing therein interconnecting the stem and the siren, said latter gearing including an automatically disengageable element 70 for permitting free overrunning of the siren whenever the vehicle decelerates faster than the natural rate of deceleration of the siren.

4. A vehicle toy comprising a toy body simulating a fire department vehicle, wheels mounted on 75

- 5 said body, a siren mounted on said body, a spring drive motor carried in said body, and gearing interconnecting the wheels, motor, and the siren to impart rapid rotation to the siren, a part of said gearing leading solely to said siren including an automatically disengageable element to permit free overrunning of the siren whenever the vehicle decelerates faster than the natural rate of deceleration of the siren.
- 10 5. In a toy automobile, a running gear, a chassis mounted thereon, a spring motor on said chassis for driving said automobile, a rotary siren having air impinging blades, one-way drive mechanism connecting said siren with said motor for producing a prolonged sound when the motor unwinds, the drive mechanism between the motor and the siren being such that the siren load including the pressure of the atmosphere against the siren blades acts as a governor to control the speed of the automobile, yet the siren is released for free overrunning rotation whenever the vehicle is stopped or decelerates faster than the natural deceleration of the siren.
